UNITED STATES PATENT OFFICE.

HANS CHRISTIANSEN, OF BEDFORD, MASSACHUSETTS, ASSIGNOR TO BEDFORD SAFETY RAZOR COMPANY, OF BEDFORD, MASSACHUSETTS, A CORPORATION OF MASSACHUSETTS.

BLADE HONING OR SHARPENING MACHINE.

1,034,422.

Specification of Letters Patent. Patented Aug. 6, 1912.

Application filed February 8, 1912. Serial No. 676,471.

To all whom it may concern:

Be it known that I, HANS CHRISTIANSEN, a citizen of the United States, and a resident of Bedford, in the county of Middlesex and State of Massachusetts, have invented certain new and useful Improvements in Blade Honing or Sharpening Machines, of which the following is a specification.

This invention has especial reference to means for honing or imparting a fine finished edge to thin flat-sided blades such as those commonly used in safety razors.

The invention has for its object to provide an automatic machine adapted to accurately hone a plurality of blades simultaneously, each blade being first held for a predetermined period with the edge portion of one of its sides in contact with a honing cylinder, and the group of blades being then simultaneously separated from the cylinder, inverted from the honing position while separated from the cylinder to cause the sides which previously faced inwardly and more on the cylinder, to face outwardly from the cylinder, and finally held again in contact with the cylinder with the sides which previously faced away from the cylinder facing toward it, so that the edge portions of both sides of the group of blades are successively presented to the cylinder.

The invention consists in the improvements which I will now proceed to describe and claim.

Of the accompanying drawings:—Figures 1 and 2 represent plan views of parts of a machine constituting an embodiment of my invention, Fig. 1 showing the machine from one end to the transverse center, while Fig. 2 shows the machine from the transverse center to the opposite end; Fig. 3 represents an end view of the machine; Fig. 3^a represents a perspective view of the rocking arms hereinafter described, Fig. 4 represents a side view of a portion of the machine. Fig. 5 represents a section on line 5—5 of Fig. 1; Figs. 5^a and 6 represent views similar to Fig. 5, showing the operation of inverting the blades; Fig. 7 represents a section on line 7—7 of Fig. 1; Fig. 8 represents a fragmentary section on line 8—8 of Fig. 2; Fig. 9 represents a perspective view of one of the rotary bearing blocks hereinafter described; Figs. 10 and 11 represent plan views of parts of a machine constituting another embodiment of the invention, Fig.

10 showing one end portion and Fig. 11 the opposite end portion; Fig. 12 represents an end view of the machine; Fig. 13 represents a rear side elevation of a portion of the machine; Fig. 14 represents a section on line 14—14 of Fig. 10; Fig. 15 represents a section on line 15—15 of Fig. 10; Fig. 16 represents a view similar to Fig. 12 showing a different stage of the operation; Fig. 17 represents an enlargement of portions of Fig. 14; Fig. 18 represents a section on line 18—18 of Fig. 14; Fig. 19 represents a modified form of blade holder. Fig. 20 represents a section on line 20—20, of Fig. 11, the parts being in position shown by Fig. 15; Fig. 21 represents a section on line 20—20 of Fig. 11, the parts being in position shown by Fig. 16.

The same reference characters indicate the same parts in all the figures.

Referring first to Figs. 1 to 7, inclusive, 12 represents the base of the frame of the machine having bearings for the several shafts hereinafter described. 13 represents the driving shaft which extends lengthwise of the base. 14 represents a grinding cylinder which may be of any suitable material adapted to produce a fine edge on razor blades 15 bearing on its periphery. The cylinder 14 is attached to a shaft 16 journaled in bearings 17 which, in this embodiment of the invention, are vertically movable in fixed guides or housings 18, and are alternately raised and lowered by cams 19 attached to a shaft 20, the cylinder being thus alternately held in a raised position while acting on the blades, and in a depressed position while the blades are being inverted to present fresh sides to the cylinder. The shaft 20 is provided with gears 21 meshing with gears 22 on the driving shaft 13. The shaft 16 and cylinder 14 are preferably reciprocated longitudinally to distribute the wear of the periphery of the cylinder, by means comprising a lever 23 fulcrumed at 24 (Fig. 2) to the base 12, a cam 25 on a shaft 26, said cam engaging a pin 27 on one arm of the lever 23, and a grooved collar 28 attached to the cylinder shaft 16, the groove of said collar receiving a pin 29 attached to the other arm of the lever 23. A spring 30 (Fig. 2) attached to the base 12 and to the lever 23 holds the pin 27 against the cam 25, said cam being formed to cause the lever to oscillate in a horizontal plane and thus re-

75

ciprocate the shaft 16 and cylinder 14 longitudinally. The shaft 26 has a gear 31 meshing with the gear 22 on the driving shaft 13. The cylinder may be rotated by a driving belt (not shown) running on a pulley 32 (Fig. 1) attached to the shaft 16, said belt being adapted to conform to the above described vertical and longitudinal movements of the cylinder shaft.

10 The machine is organized to hone or sharpen a plurality of safety razor blades 15 simultaneously, the blades being detachably grasped by holders which are adapted to present the edge portions of the inwardly facing sides of the blades to the grinding cylinder, as shown by Figs. 3, 5 and 7, for a predetermined period until the edge portions of said inwardly facing sides are honed or completed. The blades are then, in this 15 embodiment of the invention, inverted by a sidewise swinging movement away from the cylinder through an arc of about 180 degrees to the position shown by Fig. 6 so that their completed sides face outwardly, 20 the inverted blades being finally swung edgewise through an additional arc of 180 degrees to present their now inwardly facing and unfinished sides to the cylinder. During the edgewise swinging movement of the 25 blades the cylinder is held in a depressed position, as shown by Fig. 8, until the blades are in position to be honed, the cylinder being then raised to contact with the blades, as shown by Figs. 3, 5, and 7.

30 Each blade holder is composed of an arm 33, the outer end of which is formed as a jaw 34. To the arm 33 is pivoted at 35 a jaw 36 having an arm which is pressed by a spring 37 to force the jaw 36 yieldingly toward the jaw 34, so that a blade 15, having flat parallel sides, inserted between the jaws, is grasped yieldingly thereby, stops 38 being provided to bear on the edge of the blade inserted between the jaws, and insure the 35 proper projection of the opposite or cutting edge from the jaws. Each arm 33 is connected by a horizontal pivot 39 to a rotary bearing block 40 (shown separately by Fig. 9), said block having a vertical trunnion 41 40 journaled in a bearing arm 42 attached to a supporting rod 43 which is rigidly supported by fixed standards 44, Figs. 4, 5 and 6, on the base 12. The arm 33 is adapted to swing in a vertical plane on the pivot 39, as 45 indicated by Figs. 5, 5^a and 6, to invert the blade held thereby, the blade being moved from the position shown by Fig. 5 to that shown by Fig. 6. The first part of this swinging movement is caused by the means 50 next described.

46, 46 represent cams located at opposite ends of the machine, as shown by Figs. 1 and 2, said cams being attached to the ends of the shaft 26 and rotated in the direction 55 indicated by the arrow, Fig. 3. Each cam

has the contour shown by Figs. 3, 5, 5^a and 6, and includes a projection 46^a and a tangential portion 46^b. Said cams support rocking arms 47 having pivot studs 48, Figs. 1 and 3, which are journaled in fixed bearings in the end standards 44, the two rocking arms being connected by a lifting bar 49 adapted to lift the series of knife holders, as indicated by Fig. 5^a, said bar having a series of adjustable bearing screws 50 on which 70 the arms 33 rest when the knives are being honed and when they are being raised, as shown by Fig. 5^a. The rocking arms have projections which rest on the cams 46. When the concentric portions 46^a of the 75 cams are in contact with the rocking arms, the lifting bar is supported in its lowest position and the knives bear on the grinding cylinder. When the tangential portions 46^b of the cams reach the rocking arms, the lifting 80 bar and the knife holders are swung upwardly as indicated by Fig. 5^a, until the knife holders are moved slightly beyond a vertical position when they drop by gravitation to the horizontal position shown by 85 Fig. 6, to complete the inversion of the blades, their descent being limited by a stop formed by a rack bar 52. In this way the knives are swung sidewise on a horizontal axis through an arc of about 180 degrees. 90 The rack bar 52 extends horizontally lengthwise of the machine, and its teeth engage pinions 53 (shown particularly by Fig. 9) attached to the trunnions 41. The rack bar 52 is reciprocated by a lever 54, Figs. 4 and 100 7, pivoted at 55 to the base 12, and having a stud 63 engaged by a cam 57 on the shaft 26, and a slot 58, Fig. 4, which receives a stud 59 on the rack bar. A spring 62 engaged with the lever 54, holds the stud 63 on the 105 lever 54 against the cam 57. The cam 57 and spring 62 oscillate the lever 54, which in turn reciprocates the rack bar 52. Each movement of the rack is timed to swing the 110 knife holders horizontally from the position shown by Fig. 6 to that shown by Fig. 5, the inverted knives being thus swung edgewise through an additional arc of 180 degrees to the honing position shown by Fig. 5. It will appear by reference to Fig. 5 that 115 the cams have concentric portions 46^a which are of greater radius than the portion 46^b, and support the lifting bar depressed below the position shown by Fig. 5, while the knife 120 holders are swinging horizontally to their honing position, so that the bearing screws 50 will not touch the knife holders until the latter have completed their horizontal movement, the lifting bar being then raised by the intermediate cam portions 46^b to the 125 position shown by Fig. 5. The cylinder 14 is depressed while the blades are swinging horizontally and is raised to contact with the blades after the horizontal swinging movement is completed. Since each hori- 130

zontal swinging movement of the knife holders is accomplished by a single movement of the rack bar 52, it follows that the knife holders are swung horizontally alternately 5 to the right and to the left.

I will now describe the embodiment of my invention shown by Figs. 10 to 19 inclusive. The shaft 16 of the grinding cylinder 14 has a belt-driven pulley 32 as before. 130 10 represents the driving shaft having a cam 131 which coöperates with a spring 132, a lever 133 and a grooved collar 134 in reciprocating the cylinder while it is rotating. The blade holders are constructed like those 15 above described but are differently inverted. The arm 33 of each holder is provided with a trunnion 135 which is journaled in a bearing in a rocking block 136, the trunnion being located at right angles with the cutting edge of the blade held by the holder and the blade being inverted by a partial rotation of the trunnion in the block 136 so that the blade is turned on an axis at 20 right angles with its cutting edge, and passing therethrough and parallel to the flat sides of the blade. The blocks 136 are mounted to oscillate on a horizontal rod 137 supported by fixed standards 138. To each trunnion 135 is attached a pinion 139. 25 30 140 represents an elongated rack bar, the teeth of which engage all the pinions 13, as shown by Figs. 10 and 11. The rack bar 140 is adapted to be reciprocated longitudinally on studs 141 attached to oscillatory 35 arms 142 which are supported by the rod 137 and are adapted to be oscillated by cams 143 on the shaft 130, the rack bar being provided with slots 144, Figs. 10, 11 and 13 through which the studs 141 pass, said slots 40 permitting the rack bar to be reciprocated longitudinally. The arms 142, the blocks 136 with the blade holders supported thereby, and the rack bar 140 are adapted to be swung upwardly by the cams 143 to raise 45 the blades from the cylinder to the position indicated by Fig. 16. The rack bar 140 is moved endwise in one direction when in the raised position last described and is thus caused to impart a half rotation to the blade 50 holders through the pinions 139 and thus invert the blades 15 and cause the sides which before faced outwardly, to face inwardly, and bear on the cylinder when the blade holders are returned to their honing 55 position shown by Figs. 12, 14, 15 and 17. The return of the blade holders to their honing position is caused by gravitation when the cams 143 recede from the arms 142, the 60 holders swinging downwardly until the blades bear on the cylinder, which arrests the downward movement of the blades and holders before the completion of the downward movement of the arms 142 and rack bar 140, so that the rack bar is disengaged 65 from the pinions 139, as shown by Figs. 14

and 15, before its return endwise movement, the blade holder-rotating movement of the rack bar occurring when the holders and rack bar are raised, and the teeth of the rack bar are engaged with the pinions 139, 70 while the return movement of the rack bar occurs when its teeth are separated from said pinions and the blades rest on the cylinder. The mechanism which reciprocates the rack bar includes a cam 146 on the shaft 130, a lever 147, Fig. 13, pivoted at 148 and having a stud 149 bearing against the cam 146, and a stud 150 at its upper end, a grooved sleeve 151 adapted to slide on the fixed rod 137 and engaging the stud 150, a rod 152 attached to the sleeve 151 and engaged with an arm 153 attached to the central portion of the rack bar, and a spring 154 attached to the lever 147 and to a fixed support (not shown) said spring pressing the upper arm 80 of the lever toward the left as viewed in Fig. 13, and acting through the sleeve 151 and rod 152 to move the rack bar in the same direction, the stud 149 being held against the cam, which therefore acts 85 through the lever, sleeve, and rod, to move the rack bar in the opposite direction. 155 represents a fixed stop bar supported by posts 156 and provided with adjustable bearing screws 157 arranged to limit the 90 downward movement of the blocks 136, as shown by Fig. 13. Each block 136 is provided with a handle 158 by which it may be swung independently to the position shown by dotted lines, Fig. 12, to press the arm of the jaw 36 against a fixed stop bar 159 and thus release the hold of the jaws on the interposed blade and permit its easy removal.

It will now be seen that in each embodiment of the invention the blades are held 105 simultaneously against the cylinder until the inner sides of their cutting edges are treated, then separated from the cylinder and inverted, and then simultaneously presented to the cylinder with untreated sides 110 in contact therewith, provision being thus made for the honing of the inner sides of a number of blades simultaneously and for the successive presentation of the two sides of the series of blades to the cylinder, the 115 operation of the machine being automatic after the insertion of the blades in the holders.

In each embodiment of the invention all the blade holders are adapted to swing simultaneously on an axis common to all the holders and arranged parallel with the axis of the cylinder, and each holder is adapted to swing about an independent axis formed by the trunnions 41, in the first-described 120 embodiment, and by the trunnions 135 in the embodiment last described, operating mechanism being provided in each embodiment for swinging the holders simultaneously on their common axis, and for swing- 125 130

ing the holders simultaneously about their independent axes. The bearing blocks 40 and trunnions 41 are in effect parts of the blade holders.

5 While the machine is intended for honing blades that have been previously ground to an approximately finished edge, it may be used or adapted for use in sharpening blades which have not been previously 10 ground, without departing from the spirit of the invention.

I claim:

1. In a machine of the character stated, the combination of a rotary sharpening cylinder, a series of movable blade holders adapted to hold a plurality of blades simultaneously against the cylinder, said holders being adapted to swing in unison on an axis common to all the holders and parallel with 20 the axis of the cylinder, and each holder being adapted to swing about an independent axis at right angles with the axis of the cylinder, and holder-operating mechanism having means for causing simultaneous 25 swinging movements of the holders on their common axis, and means for causing simultaneous swinging movements of the holders about their independent axes.

2. In a machine of the character stated, 30 the combination of a rotary sharpening cylinder, a series of movable blade holders adapted to hold a plurality of blades simultaneously against the cylinder, said holders being adapted to swing in unison on an axis common to all the holders and parallel with the axis of the cylinder, and each holder being provided with a journaled trunnion constituting an independent axis arranged at right angles with the axis of the cylinder, 35 and provided with a pinion, and holder-operating mechanism comprising means for causing simultaneous swinging movements of the holders on their common axis, an elongated rack engaged with said pinions, and means for moving said rack to cause simultaneous swinging movements of the holders about their independent axes.

3. In a machine of the character stated, 40 the combination of a rotary sharpening cylinder, a series of blade holders adapted to swing on axes parallel with the axis of the cylinder to invert the blades, and on axes at right angles with the axis of the cylinder

45 to move the blades edgewise into position for sharpening, and mechanism for successively swinging the blade holders on said axes.

4. In a machine of the character stated the combination of a rotary sharpening cylinder, a series of blade holders adapted to 60 swing on axes parallel with the axis of the cylinder to invert the blades, and on axes at right angles with the axis of the cylinder to move the blades edgewise into position for sharpening, mechanism for successively 65 swinging the blade holders on said axes, and mechanism for alternately depressing and raising the cylinder.

5. A machine of the character stated comprising a rotary sharpening cylinder, a series of blade holders, means pivotally connecting said holders with fixed supports adjacent to the cylinder, said means having provisions for permitting the holders to swing on horizontal axes parallel with the 75 axis of the cylinder, and on vertical axes at right angles with the axis of the cylinder, a lifting bar adapted to simultaneously engage the series of holders, means for moving said bar to simultaneously swing the 80 holders on their horizontal axes, and means for simultaneously swinging the holders on their vertical axes.

6. In a machine of the character stated, 85 the combination of a rotary sharpening cylinder, a series of bearing arms rigidly supported at one side of the cylinder, a series of bearing blocks adapted to turn on said arms, a series of blade holders adapted to swing on said bearing blocks, a lifting bar 90 adapted to simultaneously engage said holders and swing them from the cylinder to a position to cause a further swinging movement of the holders by gravitation, means for raising and depressing said bar, means 95 for arresting the gravitating movement of the holders, and means for simultaneously turning the bearing blocks to move the holders into position over the cylinder.

In testimony whereof I have affixed my 100 signature, in presence of two witnesses.

HANS CHRISTIANSEN.
